CLAIM

The ornamental design for an endoscope flushing pump as shown and described.

DESCRIPTION

FIG. 1 is a front isometric view of an endoscope flushing pump.

FIG. 2 is a rear isometric view of the endoscope flushing pump of FIG. 1.

FIG. 3 is a front view of the endoscope flushing pump of FIGS. 1-2.

FIG. 4 is a rear view of the endoscope flushing pump of FIGS. 1-3.

FIG. 5 is a side view of the endoscope flushing pump of FIGS. 1-4.

FIG. 6 is an other side view of the endoscope flushing pump of FIGS. 1-5.

FIG. 7 is a top view of the endoscope flushing pump of FIGS. 1-6; and,

FIG. 8 is a bottom view of the endoscope flushing pump of FIGS. 1-7.

In the drawings, the broken lines are for the purpose of illustrating portions of the endoscope flushing pump that form no part of the claimed design.

1 Claim, 7 Drawing Sheets

Related U.S. Application Data

having an international filing date of Mar. 30, 2022,
now Pat. No. Des. 978,538.
